UNITED STATES PATENT OFFICE.

WILLIAM H. TUOHY, OF EAGLE, WISCONSIN.

CONCRETE-MOLD.

1,126,318.

Specification of Letters Patent.

Patented Jan. 26, 1915.

Application filed May 4, 1914. Serial No. 836,098.

To all whom it may concern:

Be it known that I, WILLIAM H. TUOHY, a citizen of the United States, and a resident of Eagle, in the county of Waukesha 5 and State of Wisconsin, have invented certain new and useful Improvements in Concrete-Molds; and I do hereby declare that the following is a full, clear, and exact description thereof, reference being had to the 10 accompanying drawings, and to the letters of reference marked thereon, which form a part of this specification.

This invention relates to improvements in concrete molds, and more particularly to 15 concrete molds adapted to be used in the construction of foundations and walls of the so-called "double wall" construction wherein the wall comprises a plurality of united sections constructed by the repeated 20 use of my device.

The features of my invention are directed 25 toward the construction of a mold that is universal or flexible in its use and is adapted to afford greater strength and rigidity 30 in concrete construction by permitting a solid thickness of wall to be formed at the corners or intersections of wall sections and adjacent to openings in the wall, and by the provision of a simple attachment to render the mold suitable for the building of 35 a continuous wall of the ordinary "double wall" construction.

The general features of a concrete mold embodying my invention are set forth in a 40 prior application filed by me on the 27th day of December, 1912, and bearing Serial No. 808,948.

My invention therefore consists in the 45 matters hereinafter set forth and more particularly pointed out in the appended claims and illustrated in the accompanying drawings, in which—

Figure 1 is a plan view of a form of mold 50 constituting my invention; Fig. 2 is a view in vertical section, taken on line 2—2 of Fig. 1; Fig. 3 is a view in side elevation of the said mold, with portions broken away; Fig. 3^a is a fragmentary view, taken on line 3^a—3^a of Fig. 1; Fig. 4 is a view in 55 side elevation of the block adapted to be attached to the mold when used in the construction of continuous walls; Fig. 5 is a fragmentary plan view, showing the method of constructing a continuous wall; Fig. 6 is a fragmentary plan view, showing the manner of forming a solid corner; Fig. 7

is a sectional view, taken on line 7—7 of Fig. 6; Fig. 8 is a sectional view, taken on line 8—8 of Fig. 5, showing the block attached to the mold in position for constructing a continuous wall; and Fig. 9 is a sectional view, showing a modified construction of my device.

Referring to the drawings showing a preferred embodiment of my invention, the 65 concrete mold illustrated comprises, in general, two pairs of mold boards 10, 11 and 12, 13. The pairs of mold boards are separated from each other by a space, and each pair comprises two upright mold boards arranged to be normally maintained in parallel relation and spaced apart to form a space therebetween adapted to receive the concrete for the construction of each of the sections constituting the double wall. The 70 mold boards are preferably constructed of sheet metal and are supported in upright position by means of transversely extending frame members 14, 14, provided with downwardly extending arms to which said boards 75 are secured. The arms supporting one mold board of each pair are mounted in fixed relation to the frame members and the arms supporting the other mold board of each pair are pivotally mounted upon the frame 80 members to permit a limited movement of the bar supported thereby for the purpose of attaching the mold board to and releasing the same from the already completed 85 portions of the wall. A manually operated 90 means is further provided in connection with each frame member for the purpose of simultaneously controlling the movement of the pivoted arms and the mold board secured thereto.

Referring now more in detail to the construction of my device, the mold boards 10, 11, 12 and 13 are arranged with their upper and lower margins in parallel relation. The spaces between the boards 10 and 11, or 12 100 and 13, of each pair, are preferably equal, and the distance between the inner boards 11 and 12 corresponds with the desired width of the space between the parts of the double wall to be formed by the use of the 105 device. The outer mold boards 10 and 13 project, at one end of the mold, a considerable distance beyond the ends of the inner mold boards 11 and 12. The space between the ends of the inner mold boards, at the 110 same end of the mold and at the opposite end thereof, is closed by means of trans-

versely extended members 12^a, 12^b, preferably attached to or formed on the mold board 11, and extending to and overlapping the adjacent end of the mold board 12. The 5 transverse members may have the form of removable or detachable gate members, such as are shown in my prior application, but the form thereof illustrated is preferred for use in molds in which the two pairs of mold 10 boards are not adjustable with respect to their distance apart. The outer mold boards project beyond the inner mold boards a distance preferably about equal to the distance between said outer mold boards, so that there 15 is formed at one end of the mold a rectangular space, which is separated from the space between said inner boards by the transverse member 12^a. The upper margins of the mold boards, by preference, lie in substantially 20 the same horizontal plane. The lower margins of the outer mold members 10 and 13, however, project some distance below the lower margins of the inner mold boards 11 and 12, as shown in Fig. 3. The frame 25 members 14, 14 extend transversely of the said mold boards and are spaced a suitable distance for properly supporting the boards and for operating the mold, one of said frame members being preferably adjacent to the transverse member 12^a at the shortened 30 ends of the inner mold boards 11 and 12. Each frame member comprises a rectangular structure consisting of pairs of horizontal bars 15, 16, arranged in parallel relation, 35 one above the other, and rigidly connected at their ends by means of vertical connecting members 17, the said connecting members extending between each pair of horizontal bars 15 and 16, and act to hold the 40 said bars at a distance apart to form the space between them. A plurality of rivets 18 extend through the ends of the bars, thus completing the rigid structure of the frames 14, 14.

45 Each of the frame members 14, 14 comprises a series of vertical arms 19, 20, 21 and 22, said arms extending downwardly and supporting at their lower extremities the several mold boards, there being provided suitable means for securing said arms to the outer faces of the mold boards. Two 50 of these arms 19 and 20 are secured in fixed relation to the frame and extend between the upper and lower horizontal bar members 15 and 16, the same being rigidly held in position by means of bolts 23. The arms 21 and 22 are secured to the frame members in a manner to permit them to be oscillated through a limited distance, the same being 55 pivoted to the lower horizontal bar member 16 by means of bolts 24. The arm 21 projects a distance above the upper bar member 15, whereas the arm 22 terminates between said upper horizontal bar members.

60 65 For the purpose of oscillating the boards

10 and 11, respectively, for the purpose stated, I employ the following members: Rigidly fixed to the frame member 14 is an arm 25 which projects above the horizontal bar members in vertical position. Between 70 the upper extremities of the said arm 25 and the pivoted arm 21 is mounted a turn-buckle 26 of the usual construction. The arms 21 and 22 are connected together by means of a horizontal connecting link 27 75 secured to said arms immediately below the upper horizontal bar members 15. By revolving the turn-buckle 26 in either direction the same may be extended or contracted in the well known manner, thus acting 80 to transmit a swinging movement to the movable arm 21 and likewise to the arm 22 through the medium of the connecting link 27.

The lower ends of the arms 21 and 19, 85 to which are attached the inner mold boards 11 and 12, project below the margins of said inner mold boards and terminate in the plane of the lower margins of the outer mold members 10 and 13. These end portions are bent inwardly in vertical alignment with the inner surface of said boards 11 and 12, and are extended below the lower edges of said boards to provide, in effect, a plurality of clamping lugs 19^a and 21^a, the 95 purpose of which will be apparent as I proceed with the description of the operation of my device.

One of the outer mold boards, shown herein as the board 13, is provided at its 100 lower margin with a rectangular recess 13^a, formed by rabbeting a portion of the board, at its lower margin and at the end thereof extending below the inner mold boards. The recess extends inwardly from the outer 105 extremity of the board 13 a distance equal to the distance between the outer boards 10 and 13, that is, to a point opposite the transverse portion 12^a of the inner mold board 11. The width of the recess 13^a is equal to 110 the distance which said outer board 13 projects below the inner mold boards.

The operation of constructing the walls of the so-called double wall construction is, as before suggested, accomplished by the 115 repeated use of my device and in the following manner: In Figs. 6 and 7 is shown a portion of a wall 30, already completed, with the mold secured thereto in position to receive the concrete for the formation of 120 a section of the wall to be superimposed upon said completed portion, and also in position to form the junction of two intersecting sections of the wall meeting at right angles. To secure the mold in position the 125 turn-buckle 26 is manipulated so that the movable mold boards 10 and 12 are swung in a direction away from the stationary mold members 11 and 13, respectively. By this operation the space between the pairs 130

of mold boards is increased sufficiently to allow the upper portion of the completed portion of the wall 30 to pass between the boards. The device is placed in position 5 with the lower margins of the outer mold boards slightly overlapping the outer surface of each wall portion and the clamping members 19^a and 21^a at the lower extremities of the arms 19 and 21, respectively, also 10 overlapping the upper margins of the inner surface of the wall. By again manipulating the turn-buckle, the movable mold boards are carried inward toward the stationary mold boards, thereby acting to 15 clamp the mold boards to the walls in position to be filled with concrete in the usual manner. The purpose of the clamping lugs will be now apparent, namely, to provide means for clamping both pairs of mold 20 boards to both walls and at the same time provide that the lower margins of the inner boards 11, 12 shall terminate at the upper margins of the walls, so as not to interfere with the reinforcing rods or members 25 which may be placed in the walls in a manner to extend across the space separating the said walls. Although the mold may be used to form a straight or continuous wall, the form herein shown is more particularly 30 designed for the formation of corners and door and window openings, whereby a solid wall may be produced at said corners and at the sides of such openings. As shown in Figs. 6 and 7, the mold 35 is clamped to the wall and in position for forming a solid corner, as above suggested. In this position the ends of the outer mold boards 10 and 13 project slightly beyond the end of the wall and between said ends is 40 inserted a gate member 31. This gate member may be of any suitable form, although a piece of board of suitable length and thickness and having a width equal to the distance between the outer boards is 45 adequate. This member is held in position by the clamping action of the outer mold boards and forms an end closure for the mold. In this position of the mold the recess 13^a (Fig. 7) receives the intersecting portion 50 of the wall, thus permitting the end of the outer mold board 13 to extend over the said intersecting portion without interfering with the proper positioning of the mold board in horizontal relation to the wall. 55 The mold is now ready to receive the concrete, which is placed between the inner and outer mold boards and within the space beyond the ends of the inner mold boards formed by the outer mold boards and the member 31. The transverse wall portion 12^a thus acts to form an end wall for the space between the inner mold boards so that the corner formed by the intersecting sections of the wall 30 may be of solid construction 60 by the omission of the space 65 which is ordinarily formed throughout the straight portions of the wall. When the concrete is sufficiently hardened, the mold may be released by manipulating the turn-buckle in the manner indicated and the 70 mold again secured to the wall in position to form the next section which in this instance would be superimposed upon the section at right angles to the section just completed. 75

In order that the mold may be used for constructing a continuous, straight wall of the "double wall" construction with the space between, and to permit the entire length of the mold to be utilized, I provide 80 a device or attachment in the nature of a removable block 32 (Fig. 4). The said block is preferably of wood and of a height equal to that of the inner mold boards and of a width substantially equal to the width 85 of the space separating the walls. The length of the block is substantially equal to the distance from the transverse member 12^a of the inner mold member 11 to the extremities of the outer mold members 10 and 90 13. The upper surface of the block is provided with an inclined or sloping surface 33, extending substantially throughout its length, as shown in Fig. 4. The rear portion 95 of said block is provided with an upwardly extending arm 34 rigidly attached to the rear surface of the block, the same being inclined slightly rearward (Figs. 4 and 5) and provided at its upper end with a hooked portion 35. Upon the lower surface 100 of the block is provided a downwardly extending projection 36, that may be made integral with the block, and the end surfaces of which are flush with the side faces of the block. As shown in Figs. 5 and 8 of 105 the drawings, the block is attached to the mold by means of the arm 34, which is adapted to engage the adjacent frame member 14 by means of the hooked extremity 35 of the arm, which enters downwardly into 110 the space between the lower horizontal bar members 16, 16 of said frame. In this position the block abuts at its rear surface 115 against the transverse member 12^a and extends therefrom in a direction toward the end of the mold, its lateral surfaces being parallel to the outer mold boards 10 and 13. When attached to the mold the lower surface of the block lies in the plane of the lower margins of the inner mold boards, and 120 the projection 36 extends downwardly below the upper margins of the walls 30, with its side faces in contact with the inner faces of said walls, into the space separating said walls. It is obvious that the said block 125 serves as an extension of the inner mold boards, so that, when the same is in use, the entire length of the mold may be utilized in the construction of the straight parts of the double wall. The projection 36 before 130

mentioned, by its contact with the inner faces of the walls, acts to maintain the block laterally in position during the operation of filling the mold with concrete. The purpose of the inclined upper surface of the block may be understood from the following: In filling the mold, with the block attached thereto, the concrete is placed at the sides of the block and tamped down so that its surface is in the same plane with, and has the same inclination as, that of the inclined top surfaces of the block. Upon removing the mold the sections thus formed on each wall have inclined end portions. Upon adding the next sections, a portion of the concrete will be deposited upon the inclined surface of the previously formed sections, and in tamping down the soft concrete thereon substantial joints are made between the previously formed and the newly added sections, the inclined surfaces affording adhesion greater than would be the case if the sections were joined by vertical end faces. Furthermore, when the joints are inclined, the pressure upon the concrete during the tamping of the same is exerted in a manner to press the newly added concrete in a downward direction on the end surface of the previously formed section, whereas it would be difficult to apply the proper pressure upon the concrete in case the end surfaces of the sections were vertical. This feature, therefore, affords greater solidity and strength in the wall, and affords a material improvement in concrete construction.

In Fig. 9 of the drawings, I have shown a modified construction in a mold embodying my invention, wherein is provided a horizontal member 12^c extending over the space between the inner mold boards 11 and 12 and throughout the length of the same. This member is, by preference, integral with or rigidly attached to the upper margins of one of the inner mold boards 12, and extends laterally over the upper margins of the other inner mold board 11. The purpose of this member or strip is to provide a closure for the space separating the boards, thereby preventing the concrete from entering this space, while the mold is being filled.

As a further means of aiding in the manipulation of the mold, in the construction of a straight or continuous wall, a removable rod 37 (Figs. 1, 5 and 8) may be provided which is adapted to extend between the ends of the outer mold boards 10 and 13, adjacent to the ends of the same and near their lower edges. Laterally alined apertures are provided in said boards to receive the said rod, said apertures being located close to the lower margins of the outer boards and substantially in the plane of the lower margins of the inner boards. When such rod is in place, it is adapted to

engage and rest upon the top surface of the previously completed wall, in a manner to support the forward end of the mold, when the latter is released from the wall. Such rod, by so supporting the mold, permits the same to be easily slid or shifted along the wall in changing its position; it being obvious that in the absence of such rod it would be necessary to lift the entire mold in moving it from one position to another, and to sustain its weight while adjusting the mold to, and clamping it in, its new position.

It is to be understood that my device may be used in the formation of openings, as for instance, to provide a window or door, the mold being manipulated in the same manner as before described in connection with the formation of a solid corner at the junction of two intersecting walls.

A concrete mold embodying the features of my invention has the advantage of materially decreasing the cost of concrete construction by the use of a single mold and a single attachment, whereby the ordinary steps may be easily and rapidly performed. Furthermore, it permits the application of the proper principles of construction without the use of special forms of molds.

The device herein illustrated and described may be variously modified in the details of construction without departing from the spirit of the invention, and for that reason I do not wish to be limited thereto, except in so far as provided in the appended claims.

I claim as my invention:

1. A concrete mold, comprising a plurality of pairs of mold boards, spaced apart from each other, the mold boards of each pair being spaced apart to receive concrete between them, and means for supporting said mold boards in spaced relation; the end of the outer mold board of each pair projecting, at the end of the same adjacent to at least one end of the mold, beyond the adjacent end of its associated inner mold board, at least one of said outer mold boards being provided with a rabbet at its lower margin extending throughout its end portion beyond said inner mold boards.

2. A concrete mold, comprising a plurality of pairs of mold boards, spaced apart from each other, the mold boards of each pair being spaced apart to receive concrete between them, a frame supporting said mold boards, the end of the outer mold board of each pair projecting, at the end of the same adjacent to at least one end of the mold, beyond the adjacent end of its associated inner mold board, the extended end portion of at least one of said outer mold boards being provided with a rabbet at its lower margin to form an end portion of reduced

width, and a transverse member extending between the ends of said inner mold boards, at the same end of the mold.

3. A concrete mold, comprising a plurality of pairs of mold boards, spaced apart from each other, the mold boards of each pair being spaced apart to receive concrete between them, and a supporting frame extending transversely of said boards, the outer mold boards, at the end of the same adjacent at least one end of the mold, extending beyond the adjacent end of the inner mold board, the extended end portion of at least one of said outer mold boards being provided with a rabbet at its lower margin to form an end portion of reduced width, and one end of said inner mold boards being provided at the same end of the mold with a transverse portion attached thereto and extending across the space between said inner mold boards.

4. A concrete mold, comprising a plurality of pairs of mold boards, spaced apart from each other, the mold boards of each pair being spaced apart to receive concrete between them, a supporting frame extending transversely of said boards, and means for supporting the mold boards from said frame, embracing means for adjusting laterally one of the mold boards of each pair, the outer mold boards, at one end of the mold, extending beyond the ends of the inner mold boards, the extended end portion of at least one of said outer mold boards being provided with a rabbet at its lower margin to form an end portion of reduced width, and one of said inner mold boards being provided at said end of the mold with an end portion bent at right angles thereto and adapted to extend transversely of the space between said inner mold boards, and to overlap the end of the other of said inner mold boards.

5. A concrete mold, comprising a plurality of pairs of mold boards, spaced apart from each other to provide an air space between the walls to be formed, the boards of each pair being spaced apart to receive concrete between them, a frame for supporting said mold boards, the outer mold boards projecting, at one end of the mold, beyond the ends of the inner mold boards, for the purpose of forming a rectangular space at one end of the mold, and a solid block adapted to be detachably connected to said mold and to extend longitudinally of said mold, between and parallel with said

outer mold boards, and acting to form a continuation of the inner mold boards extending to the ends of the outer mold boards. 60

6. A concrete mold, comprising two pairs of mold boards, spaced apart to provide an air space between the walls to be formed, the mold boards of each pair being spaced apart to receive concrete between them, the outer mold boards extending, at one end of the mold, beyond the ends of the inner mold boards, through a rectangular space at one end of the mold, one of said inner mold boards being provided with a transverse portion extending between the ends of said inner mold boards, a supporting frame extending transversely of said mold boards adjacent to said transverse portion, and a block adapted to extend longitudinally of the mold from the ends of the inner mold boards between the outer mold boards, and to abut at its rear surface against said transverse portion, said block being provided with an inclined upper surface and upon its rear surface with an upwardly extending arm having a hooked extremity adapted to engage said supporting frame. 70

7. A concrete mold, comprising two pairs of mold boards, spaced apart from each other, the mold boards of each pair being spaced apart to receive concrete between them, a supporting frame extending transversely of said mold boards, the outer mold boards extending, at one end of the mold, beyond the ends of the inner mold boards, one of said inner mold boards being provided with a transverse portion extending between the ends of said inner mold boards, and a block adapted to extend longitudinally of the mold from the ends of the inner mold boards between the outer mold boards, and to abut at its rear surface against said transverse portion, said block being provided upon its rear surface with an upwardly extending arm having a hooked extremity adapted to engage said supporting frame, and also provided with a downwardly extending projection flush with the side faces of the block. 100

In testimony that I claim the foregoing as my invention I affix my signature in the presence of two witnesses, this 30th day of April A. D. 1914.

WILLIAM H. TUOHY.
